UNITED STATES PATENT OFFICE.

RAYMOND CROWDER, OF EDGEWOOD, PENNSYLVANIA, ASSIGNOR TO GUARANTEE LIQUID MEASURE COMPANY, OF ROCHESTER, NEW YORK, A CORPORATION OF DELAWARE.

DESIGN FOR A GLOBE FOR LIGHTING-FIXTURES.

53,145.

Specification for Design.

Patented Apr. 1, 1919.

Application filed March 8, 1918. Serial No. 221,316. Term of patent 14 years.

To all whom it may concern:

Be it known that I, RAYMOND CROWDER, a citizen of the United States, residing at Edgewood, in the county of Allegheny and State of Pennsylvania, have invented a new, original, and ornamental Design for Globes for Lighting-Fixtures, of which the following is a specification, reference being had to the accompanying drawing, forming a part thereof.

Figure 1 is a front side view of a globe embodying my design;

Fig. 2 is a top plan view showing the triangular shape;

Fig. 3 is a view taken on a line with one of the edges of the globe and showing two sides thereof.

My globe is composed of translucent material and comprises base 2, top 3 and sides 4. Each side 4 has a circular portion 5 surrounded by an indented or grooved border 6.

I claim:—

The ornamental design for a globe for lighting fixtures, as shown and described.

In testimony whereof I hereunto affix my signature.

RAYMOND CROWDER.
